CLAIM

The ornamental design for long blade roller skate, as shown and described.

DESCRIPTION

FIG. 1 is a perspective view of a long blade roller skate showing my new design;

FIG. 2 is a side elevational view thereof, the side opposite being a mirror image;

FIG. 3 is a top plan view thereof;

FIG. 4 is a bottom plan view thereof;

FIG. 5 is a front elevational view thereof;

FIG. 6 is a rear elevational view thereof;

FIG. 7 is a perspective view of a modified embodiment of the design shown in FIGS. 1 through 6;

FIG. 8 is a side elevational view of the embodiment of FIG. 7, the side opposite being a mirror image;

FIG. 9 is a top plan view of the embodiment of FIG. 7;

FIG. 10 is a bottom plan view of the embodiment of FIG. 7;

FIG. 11 is a perspective view of another embodiment of the design shown in FIGS. 1 through 6;

FIG. 12 is a side elevational view of the embodiment of FIG. 11, the side opposite being a mirror image;

FIG. 13 is a top plan view thereof; and

FIG. 14 is a bottom plan view thereof.

The unshown front and rear elevational views of the embodiments disclosed in FIGS. 7-14 are identical to those shown in FIGS. 5 and 6.
